US0D1044444S

(12) **United States Design Patent** (10) **Patent No.:** **US D1,044,444 S**
(45) **Date of Patent:** **** Oct. 1, 2024**

(54) **HAND TOOL**

(71) Applicant: **Hanlong Industrial Co., Ltd.**, New Taipei (TW)

(72) Inventor: **Pai-Wei Lin**, New Taipei (TW)

(73) Assignee: **Hanlong Industrial Co., Ltd.**, New Taipei (TW)

(**) Term: **15 Years**

(21) Appl. No.: **29/839,071**

(22) Filed: **May 18, 2022**

(30) **Foreign Application Priority Data**

May 12, 2022 (TW) 111302281

(51) **LOC (14) Cl.** **08-05**

(52) **U.S. Cl.**

USPC **D8/52**

(58) **Field of Classification Search**

USPC D8/52, 107, 54
CPC H02G 1/1214; H02G 1/1212; B25B 7/00

(57) **CLAIM**

The ornamental design for a hand tool, as shown and described.

DESCRIPTION

FIG. 1 is a perspective view of a hand tool in accordance to an embodiment of the design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines are included for the purpose of illustrating portions of the hand tool and form no part of the claimed design.

1 Claim, 6 Drawing Sheets
